UNITED STATES PATENT OFFICE.

JOHN SHARP, OF OAKMONT, PENNSYLVANIA, ASSIGNOR TO ALUMINUM SEAL COMPANY, OF NEW KENSINGTON, PENNSYLVANIA, A CORPORATION OF PENNSYLVANIA.

CAP-CENTERING DEVICE FOR BOTTLE-CAPPING MACHINES.

Application filed April 8, 1921. Serial No. 459,664.

My invention relates to a cap centering device for bottle capping machines such as illustrated and described in my Patent No. 1,440,246, issued on Dec. 26, 1922.

- 5 The object of the present invention is to provide a centering device for the cap, situated in such close relation to the cap seating plunger that the proper centering of the cap will always be assured before the cap 10 comes into contact with the cap-seating plunger. Heretofore in machines of this character the centering device has been carried by a stationary frame at a point considerably below the cap seating plunger and the cap 15 might, under such conditions, become off-center before reaching the cap-seating plunger, and liability to such disarrangement of the cap is practically precluded by my invention.
- 20 In the accompanying drawing, Fig. 1 is a vertical sectional view of the aligned receptacle-supporting pedestals and the cap-applying mechanism, showing the cap being secured to the bottle neck and just prior to 25 the completion of the capping operation; Fig. 2 is a like view illustrating the relative position of the bottle support and the cap-applying mechanism prior to the capping operation; and Fig. 3 is an enlarged plan view of the centering device looking from 30 below.

In the drawing the numeral 5 indicates a fragment of the lower table or frame in which the vertical shaft 6 is mounted, 35 splined slidably in bearings. The shaft 6 is provided at its lower end with a roller 7 which rides on a cam track 8 on the base of the machine, said cam being for the purpose of elevating the bottles or other receptacles to engage with the cap and maintain the receptacles in elevated position while the cap is being secured.

The shaft 6 carries at its upper end a seat member 9 upon which the receptacle or bottle 40 10 is supported. This member is splined to the shaft 6 to prevent its rotation, but is free to move vertically, being resiliently supported on the shaft by a spring 11 which is interposed between said member and a collar 12, said collar being adjustable on the shaft so that the tension of the spring may be varied if desired. A centering block 13 having arms forming a V-shaped guide which engages with and centers the recep-

tacle axially of the shaft and with the cap- 55 ping mechanism. A resilient pad 14 may be provided in the seat member 9.

The plunger mechanism comprises a vertically movable non-rotary shaft 15 having its bearing in the sleeve 16 and carrying at 60 its upper end the roller 17 which is adapted to roll on a cam track 18 on the fixed head 19 of the machine. The lower end of the shaft has fixed thereto a conical plunger head 20 having its bearing in a counter bore at the 65 lower end of the sleeve. The head 20 is formed on its bottom with a depression or seat 21 against which the cap on the receptacle is adapted to seat and bear when the receptacle is elevated. The head 20 is counter-bored to receive an auxiliary plunger 22 which seats at its upper end against a compression spring 23 in the bore and which normally projects beyond the bottom of the plunger head to engage with the cap. This 70 auxiliary plunger 22 is for the purpose of engaging with the cap when the cap is stripped from the cap holder and the bottle is elevated, and insures seating of the cap on the receptacle preliminary to seating of 75 the cap against the plunger head, and acts to maintain the receptacle tight on its seat during elevation of the receptacle by the cam track 8. The upper rotary frame 24 carries a circular series of rotary cap-applying 80 mechanisms, each mechanism comprising a sleeve 16 journaled in a bearing 25 on the frame, and each has a pinion 26 which meshes with a stationary ring gear 27 on the stationary head 19 of the machine. The 85 sleeve 16 carries a plurality of rollers 28, preferably three in number, which are adapted to roll the flange or skirt of the cap to secure the cap to the receptacle as the frame 24 rotates. These rollers are journaled axially vertically on the lower ends of swinging arms 29 which are radially disposed and pivoted at 30 on the sleeve 16. The upper end of each arm 29 above the pivot point engages with a spring 31 interposed between said 90 arm and the sleeve, and each acts normally to swing the lower end of the arm toward the sleeve.

Extending down from the sleeve 16, and preferably forming part of same, are the 105 legs 32 with the threaded apertures 33 formed therein. Secured to the legs 32 by means of screws 34 is the cap guide-plate 35

with the downwardly flaring opening 36 through which the neck of the bottle with the cap thereon travels to seat said cap in the seat 21 of the plunger head 20, as shown in Fig. 1. The guide-plate 35 has the centering lugs 37 which engage the inner faces of the legs 32. The upper face of the guide-plate 35 has the beveled portions 38 which register with the rollers 28, and said beveled portions 10 permit of the rollers moving inwardly during the rolling of the cap, without interference on the part of said guide-plate, as clearly indicated in Fig. 1.

It will be observed that where the lugs 37 occur in the guide-plate 35, said guide-plate is thicker and these portions occur between the rollers 28. As a consequence there is a greater bearing surface at these points in the flaring opening 36, as indicated in Fig. 2, thereby bringing the guiding faces up closer to the seat 21 of the plunger head 20 and opposite to the skirt of the cap, at three points, as shown in Fig. 3. This is a point of great advantage, as the closer the guiding faces are to the seat 21, the less liability there will be of any disarrangement of the cap before reaching said seat. The idea is to get the guiding faces as close as possible to the plunger head without interfering with 30 the operation of capping.

When in operation the bottle or other receptacle with the cap thereon carried by the support 9 is elevated until the plunger 22 comes in contact with said cap, and by the further elevation of the bottle the plunger is forced upwardly compressing the spring 23 and the cap, passing up through the opening 36 in the guide-plate 35, if canted or tilted from one side to the other comes in contact with the flaring walls of the opening 36 in the guide-plate 35, and its position is corrected so as to be in proper position to enter the seat 21 in the plunger head 20. In view of the fact that the guide-plate 35 is located up close to the plunger head the position of a tilted cap is corrected just before 40 45

it enters said seat. When the cap has been seated in the seat 21, the rollers 28 are then brought into position to roll the cap, as indicated in Fig. 1, in the ordinary manner, and it is not deemed necessary to go into this operation in detail, except to say that the guide-plate 35, being secured to the sleeve 16, rotates with said sleeve and the rollers carried by said sleeve. 50 55

What I claim is:

1. In a device of the character described, the combination of a sleeve member having rotary movement only, rolls carried thereby, a vertically movable plunger carried by said sleeve and having a cap seat, a yieldingly mounted plunger carried by said first plunger, legs on said sleeve disposed intermediate said rolls, and a guide plate secured to said legs beneath said plungers, the said plate having a downwardly flaring opening therein, whose wall at its upper end terminates in segments disposed between the rolls, and the said yieldingly mounted plunger being normally projected into said flaring opening. 60 65 70

2. Bottle capping apparatus comprising, in combination with crimping means, a vertically movable cap seating plunger, a cap centering device disposed adjacent to the underside of said plunger but spaced therefrom, and a yieldably mounted auxiliary cap engaging plunger carried by said seating plunger and normally projecting into said cap centering device. 75 80

3. Bottle capping apparatus comprising, in combination with crimping means, a seat for supporting the cap while being crimped, a cap centering device disposed adjacent to the underside of said seat but spaced therefrom, and a yieldably mounted cap engaging plunger projecting from said seat into said cap centering device. 85

In testimony whereof I, the said JOHN SHARP, have hereunto set my hand.

JOHN SHARP.
